UNITED STATES PATENT OFFICE.

ERNEST E. CANEDY, OF NORTH ADAMS, MASSACHUSETTS.

DESIGN FOR A HOLDER FOR SHOE-RACKS.

SPECIFICATION forming part of Design No. 29,334, dated September 13, 1898.

Application filed August 10, 1898. Serial No. 688,308. Term of patent 3½ years.

To all whom it may concern:

Be it known that I, ERNEST E. CANEDY, a citizen of the United States, residing at North Adams, in the county of Berkshire and State 5 of Massachusetts, have invented and produced a new and original Design for Holders for Shoe-Racks, of which the following is a specification.

My invention relates to a new and novel design for a holder for shoe-racks; and the leading feature consists in the peculiar shape or configuration given to the same, whereby a neat and ornamental appearance is presented.

In the accompanying drawings, Figure 1 is 15 a perspective view of a holder constructed according to my design. Fig. 2 is a plan view of the same. Fig. 3 is an end view.

In the said drawings, the reference-letter A designates the holder, bent at or near the center, forming an upwardly-extending hook B. Said holder is then bent laterally outward in

opposite directions, forming two longitudinal arms A', and then bent backwardly, forming two parallel arms A'', the extremities of which are bent into eyes C, which are connected 25 with each other.

A holder constructed as above will present an ornamental appearance and can be readily distinguished from articles of like character now in use.

Having thus fully described my invention, 30 what I claim is—

The design for a holder for shoe-racks, substantially as herein shown and described.

In testimony whereof I have hereunto set 35 my hand in presence of two subscribing witnesses.

ERNEST E. CANEDY.
